UNITED STATES PATENT OFFICE

91,838

DESIGN FOR AN AIR CONDITIONING UNIT

Charles A. Olson, John P. Magos, and Malcolm W. McRae, Chicago, Ill., assignors to Crane Co., Chicago, Ill., a corporation of Illinois

Application January 27, 1934, Serial No. 50,528

Term of patent 14 years

To all whom it may concern:

Be it known that we, CHARLES A. OLSEN, JOHN P. MAGOS, and MALCOLM W. MCRAE, citizens of the United States, residing at Chicago, in the county of Cook and the State of Illinois, whose post-office addresses are 836 South Michigan Avenue, Chicago, Illinois, have invented a new, original, and ornamental Design for an Air Conditioning Unit, of which the following is a specification, reference being had to the accompanying drawings, forming part thereof.

In the drawings:

Fig. 1 shows a perspective view of the unit in its

complete assembly for heating or cooling when using a steam or hot water boiler as a source of heat.

Fig. 2 shows a perspective view of the same unit as adapted for use with a warm air furnace as a source of heat and having the cooling element housed in the base section.

We claim:

The ornamental design for an air conditioning unit substantially as shown and described.

CHARLES A. OLSON.
JOHN P. MAGOS.
MALCOLM W. MCRAE.
